(57) **CLAIM**

The ornamental design for a wedge tool, as shown and described.

DESCRIPTION

FIG. 1 is a top perspective view of a wedge tool showing the new design;

FIG. 2 is a bottom perspective view;

FIG. 3 is a top view;

FIG. 4 is a bottom view;

FIG. 5 is a side view, the opposite side being a mirror image;

FIG. 6 is a front view; and,

FIG. 7 is a rear view.

The broken lines illustrate portions of the wedge tool that form no part of the claimed design.
